UNITED STATES PATENT OFFICE.

ISAAC N. BUCK, OF ELGIN, ILLINOIS.

SASH-FASTENER.

SPECIFICATION forming part of Letters Patent No. 308,055, dated November 18, 1881.

Application filed May 10, 1884. (No model.)

To all whom it may concern:

Be it known that I, ISAAC N. BUCK, of Elgin, in the county of Kane and State of Illinois, have invented certain new and useful Improvements in Sash-Fasteners; and I do hereby declare that the following specification, taken in connection with the drawings furnished and forming a part of the same, is a clear, true, and complete description of my invention.

10 Sash-fasteners embodying my invention belong to that general class of fasteners which are applied to the meeting-rails of sashes; and the prime feature of novelty consists in the employment of two co-operating pivoted 15 "sweeps" or locking-bars which are controlled by a thumb-lever, so that said sweeps are caused to approach each other in the arc of a circle, and to embrace a portion of the keeper, and thereby draw the sash together, 20 their presence in a horizontal slot in said keeper serving to lock both sashes against vertical movement. The keeper is novel in that it is a rectangular plate in cross-section, affording a base and a vertical lip, the latter being longitudinally slotted on each side of a central portion which is embraced by the sweeps. I also 25 rotatively couple the sweeps and provide the thumb-lever with a spring, and suitable notched seats, whereby both sweeps are securely held either in their locked or their unlocked 30 positions. I also provide said sweeps with a spring or springs, whereby they are thrown from their unlocked to their locked position, although without departure from certain portions of my invention said spring or springs 35 may be reversely applied and relied upon solely for throwing said sweeps from their locked to their unlocked position. With the sweeps and their spring or springs which throw the 40 sweeps from their unlocked position I employ with the spring thumb-lever a releasing-bolt, which on striking one portion of the keeper trips the lever from its retaining-notch and allows the sweeps to be automatically thrown 45 from their unlocked to their locked position.

All of the several features of invention may be embodied in one structure, or some of said features may be employed independently of others, and in either case the resulting sash-fasteners will afford extraordinary security, confine the sash against undue rattling, and be convenient in use.

Referring to the drawings, Figure 1 is a plan or top view of one of my fasteners and its keeper as if applied to sashes and in a locked 55 position. Fig. 2 is a similar view of the fastener in its unlocked position and with its top plate broken away to disclose its interior. Fig. 3 is a front or edge view of the fastener. Fig. 4 illustrates a keeper in front view and 60 in vertical cross-section. Fig. 5 is a perspective view of the thumb-lever detached. Fig. 6 is a perspective view of one of the sweeps detached. Fig. 7 is a view of the sweep-springs detached. Fig. 8 is a detached view 65 of the spring latch-bolt, which on striking the keeper releases the thumb-lever from its notch. Fig. 9 is a plan view of the sweeps with their spring applied for throwing them from their locked to their unlocked position. Fig. 10 is 70 a plan view of my fastener and its keeper, both in a slightly modified form. Fig. 11 is a front and top view of the keeper of Fig. 10. Fig. 12 is a perspective view of one of the sweeps of the fastener, Fig. 10, detached. Fig. 13 is a 75 rear view of the casing. Fig. 14 is a sectional view of the fastener on line *x*, Fig. 2.

The keeper A is rectangular in cross-section, and has a base-plate, *a*, provided with screw-holes for securing it to a sash, and a vertical lip, *a'*, and two horizontal slots, *a''*, one on each side of a central post, *a'''*. As shown in Fig. 4, the post *a''* at each side is rounded or chamfered, and it has in its front face a central recess, *a''''*, in a vertical line, and having 85 at its bottom an inclined surface.

The fastener B comprises a suitable casing provided with screw-holes for enabling it to be secured to a sash, and having a base-plate, *b*, a top plate, *b'*, and a rim-plate, *b''*. It is 90 immaterial how these portions of the casing are constructed, or how they are united, so long as provision is made for properly assembling and mounting the working parts of the fastener therein. The curved or bow-shaped sweeps *c* and *c'* are substantially counterparts, and both of them have their outer ends curved toward each other, and are both pivotally mounted in the casing, so that said outer ends swing toward and away from each 95 other in the arc of a circle. Both sweeps adjacent to their pivots or axes are constructed in the form of toothed segments, which mesh with each other, and the sweep *c* is provided

with a pivoted thumb-lever, d , so that when said lever is moved to and fro both sweeps, being coupled, are simultaneously caused to emerge from and retire within the casing, and 5 said casing is provided with notches d' , as shown in Fig. 13, into which the thumb-lever d can be placed for locking or holding and thereby securing both sweeps in their protruded or their retired positions.

10 As thus far described these parts constitute a novel fastener of considerable value, it being obvious that by swinging the thumb-lever both sweeps will be made to enter the slots a^2 and with their outer ends pass to the rear of 15 the post a^3 , and by engaging therewith draw the sashes together; and also that the sweeps by occupying the slots lock the sashes against vertical movement. Each sweep being curved and in the arc of a circle renders it practically impossible for either of them to be disengaged from the keeper by means of a knife-blade, for instance, entered by way of the space between the sashes, even if the thumb-lever 20 be not properly engaged with its locking-recess. For still greater security, however, I provide these sweeps with springs, which throw them outward from the casing when permitted so to do by the thumb-lever, and hold them in a locked position, and with a view to economy I make practically one spring serve for 25 both sweeps, or rather I form two springs, e , of one continuous piece of wire, the terminals of which hook upon studs e' on the sweeps.

I also provide the pivoted thumb-lever d 30 with a spring, d^2 , as seen in Fig. 14, which causes the outer end of said lever to be normally forced upward, or in the direction of its locking notches d' , in a manner well known.

While I prefer the sweep-springs to be so 35 arranged as to throw the sweeps outwardly from the casing, I am aware that it is sometimes deemed desirable to have the sweeps provided with a spring or springs which will throw them from their protruded or locked 40 position to their unlocked or retired position, as illustrated in Fig. 9, and it is obvious that the spring shown needs only to be reversed for thus varying its action, and I therefore 45 do not preclude myself from employing either 50 of these particular arrangements of the sweep-springs.

Recognizing the limited demand for an automatically-operated sash-fastener, which when the lower sash has been brought to its seat 55 will be automatically sprung and locked, I have devised a spring latch-bolt, f , which, by contact with the inclined surface of the central recess, a^4 , on the keeper, will cause a release of the spring thumb-lever d from its 60 retaining-notch, and allow the sweep-springs to force the sweeps outwardly into engagement with their keeper. This latch-bolt f has a protruding latch-head, f' , and its rear end at f^2 has a slightly wedge-shaped surface, which slides beneath the top plate and 65 against the upper surface of the thumb-lever, and therefore, when forced inwardly by con-

tact with the keeper, it forces the outer end of the thumb-lever downward out of its notch. The latch-bolt f is mounted upon a 70 spring, f^3 , which normally maintains the latch-head f' in its properly-protruded position. It will be seen that this latch in no manner interferes with the operation of the other portions of the fastener, but that it necessarily 75 involves, for use in combination therewith, sweep-springs which throw the sweeps outwardly from the case.

In Figs. 10, 11, and 12 I show my fastener and its keeper in a slightly modified form. 80 The keeper A has the central post, a^3 , and the horizontal slots a^2 are open at each end of the keeper, and the sweeps are slightly longer than those before described, and have vertical studs c^2 at their outer ends, which engage with the rear edge of the vertical lip a' , which is curved to generally conform to the arc of the circle in which the outer ends of the sweeps are moved. The top plate of the casing is recessed near its edge for the reception of the studs c^2 when the fastener is in its unlocked condition.

I am aware that piano-locks, &c., have heretofore contained two co-operating pivoted bolts, and also that two pivoted cams geared together have been operated by a lever for use as a window lock and catch when applied to a window-frame, and arranged to bear against a vertical surface on a sash at one side thereof; but I am not aware that any prior 90 sash-fastener has embodied a pair of curved sweeps coupled together and arranged to engage with a keeper as now invented by me.

Having thus described my invention, I claim as new and desire to secure by Letters Patent— 105

1. In a sash-fastener, the combination, substantially as hereinbefore described, with a keeper having a central post and a slot on each side thereof, of a pair of pivoted curved sweeps geared together, and a thumb-lever 110 connected to one of said sweeps for simultaneously controlling both sweeps with reference to their engagement with or disengagement from said keeper.

2. In a sash-fastener, the combination, with 115 a casing, of a pair of pivoted curved sweeps coupled together, a thumb-lever, notches in the casing for holding said lever in position, and a spring or springs for said sweeps, substantially as described.

3. In a sash-fastener, the combination, with a keeper, a pair of curved sweeps, their springs for throwing them into a locked position, and a thumb-lever for holding said sweeps in their unlocked position, of a latch-bolt substantially as described, whereby when said latch-bolt strikes the keeper the thumb-lever is made to release the sweeps and permit them to automatically engage with the keeper, as set forth.

ISAAC N. BUCK.
